LEG, KNEE, AND FOOT GUARD AND SUPPORT

David A. Holder, Goldsboro, N. C.

Application September 28, 1953, Serial No. 382,596

4 Claims. (Cl. 2—22)

This invention relates to improvements in pads and supports for protecting and supporting without strain the knee, leg and foot of a wearer while in kneeling position.

A further object of this invention is the provision of an improved supporting and guard device adapted to be worn by individuals who are compelled to kneel while performing work for supporting the wearer's leg and foot in comfort, without the incidental strain.

A further object of this invention is the provision of an improved low cost, efficient comfort providing device adapted to be worn by those engaged in work which necessitates kneeling, such as in the agricultural industry, incidental to picking of strawberries, cotton and other low growing crops.

Other objects and advantages of the invention will be apparent during the course of the following detailed description.

In the accompanying drawings, forming a part of this specification, and wherein similar reference characters designate corresponding parts throughout the several views:

Fig. 1 is a perspective view showing the application of the improved knee, leg and foot guard and support upon a wearer.

Fig. 2 is a fragmentary view, partly in section, showing details of the preferred form of guard and support.

Fig. 3 is a front elevation of the guard and support of Fig. 2.

Fig. 4 is a cross sectional view taken substantially on the line 4—4 of Fig. 3.

Fig. 5 is a vertical cross sectional view taken through a modified form of knee, leg and foot guard and support.

Fig. 6 is a front elevation of the support of Fig. 5.

Fig. 7 is an enlarged transverse cross sectional view taken through the guard and support of Fig. 5, substantially on the line 7—7 of Fig. 5.

In the drawings, wherein for the purpose of illustration are shown different forms of the invention, the letters A and B may generally designate the forms of invention shown in Figs. 2 and 5 respectively. Each of the same includes a main casing or frame supporting padded body portion 10, with associated adjustable foot supporting and rest members 11 and 12 respectively provided for the forms of invention A and B.

The body portion 10 of both forms of invention A and B, preferably comprises an elongated rigid frame or casing portion 11^a having a longitudinally and lower endwise opening chamber lined with padding 12 of foam rubber, felt or other material. The casing 11^a has a cup-shaped upper end portion 14 for receiving the knee, and in transverse cross section it is segmental shaped and adapted to cover the shin bone of the wearer for the major length thereof. It also extends around the sides of the leg of the wearer, as is shown in Fig. 1 of the drawings. The frame or casing portion 11^a is of one piece construction, preferably of aluminum or

2

magnesium alloy, plastic or other rigid material and to assist in maintaining it upon the leg of the wearer, at the upper and lower ends, there are provided harnesses including a strap 15, at one side, having a buckle 16 thereon, and a strap portion 17 at the opposite side perforated to receive the buckle prong. If desired, as shown in the form of invention B, the straps may take the form of a strap portion 20 threaded through an opening 21 in one of the sides of the frame 11 and secured for length 10 adjustable purposes in an adapter 22. The opposite side of the frame 11 may have a loop or staple 24 for detachably receiving a hook 25 secured to the free end of the strap 20. This will enable the straps to be quickly released from the leg. Through disconnection of the hook 25 from the loop 24 the operator will be able to quickly release the upper part of the guard below the knee from his legs in order to assist in comfortable standing.

Referring to the foot rest and support 11 for the form 20 of invention A, the same is preferably of rigid material although it may be made with some springiness to resiliently support the foot in a position without touching the ground, such as shown in Fig. 1. The same preferably includes a pair of spaced bar portions 30 and 31 25 disposed in parallelism. They are arcuated downwardly and forwardly at the lower ends thereof below the lower end of the frame 11^a, as indicated at 33 in Fig. 2 of the drawings; the said bar portions being integrally connected to a lower foot rest portion 35 which is concaved and receives an instep pad 36 of foam rubber or other material. A depending forwardly extending skid 37 is formed integral with the portion 35 and has an arcuated skid end 38, as shown in the drawings. The portion 35 of the foot support member 11 is provided with a foot 30 clamping belt assemblage 40 adapted to extend around the ball of the foot of the wearer and around the shoe, in position shown in Fig. 1, to hold the pad at the wearer's instep.

In the form of invention B, the foot guard, and support member 12 is differently constructed. It has a single straight portion 41 instead of the two bars 30 and 31 of the form of invention A.

In the form of invention A, the member 11 has the bar portions 30 and 31 each provided with a pair of elongated slots 50 adapted to receive screw threaded shanks 51 fixedly mounted upon the frame 11^a, and which shanks receive wing nuts or like clamping expedients 52 by means of which the foot guard and support may be properly supported in definite lengthwise adjustment 45 upon the frame 11^a in order to properly position the pad 35 upon the instep according to the degree of spacing of the wearer's foot from the knee.

In the form of invention B, showing the foot guard and support 12, the portion 41 is provided with a single 55 pair of longitudinally extending slots 55 adapted to receive screw threaded shanks 56 fixed upon the frame 11^a; wing nuts or like clamping members 58 cooperating to provide the desired lengthwise adjustment of the foot guard and support portion 12 upon the frame or 60 casing portion. The support 12 has a skid bar 37^a and a curved skid end 38^a. It also has an instep pad 35^a and foot attaching strap 40^a.

It will be noted that the frame or casing portions are 65 of one piece construction; the foot rest and support portions 11 and 12, being forwardly and downwardly angled with respect to the line of the casings 10, and thus directly supporting the foot and lower leg of the wearer. The foot is supported in spaced relation from the ground or surface upon which the wearer is kneeling, and the 70 weight of the foot rests at the dorsal part of the arch upon the skid or support member. Thus, the foot itself

is supported in a natural position upon the device free of strain. The skid end is spaced upwardly from the toe end of the wearer so that the wearer can walk with ease when not kneeling.

I am aware that for kneeling persons leg supports have heretofore been provided. For the most part they support the leg of the wearer in kneeling position too high above the ground and not very comfortably for picking of low crops. There is a decided strain upon the upper part of the body while in kneeling position if the leg is not slung close to and almost touching the ground. That is a feature of the present invention, as will be noted from Fig. 1, and yet the device supports the knee, leg and also foot in comfortable positions without strain.

Various changes in the shape, size and arrangement of parts may be made to the form of invention herein shown and described without departing from the spirit of the invention or scope of the claims.

I claim:

1. In a device for supporting the leg and foot of a wearer while in kneeling position the combination of a rigid elongated frame having means for attachment to the lower leg of the wearer for extension along the front of the shin bone of the wearer above the ankle, and a foot supporting ground engaging member connected to the lower portion of said frame and extending therebelow at an angle thereto and having means thereon for directly receiving and supporting the upper front portion of the foot of the wearer thereon, said ground engaging member at its extreme end remote from the frame constituting a ground engaging skid.

2. A device as set forth in claim 1 whereon the skid is provided with a ground engaging curved surface to facilitate sliding along a ground surface.

3. In a device for supporting the leg and foot of a wearer while in kneeling position the combination of an elongated rigid frame having socket means for attachment to and reception of the lower leg of the wearer along the shin bone of the wearer above the ankle, and a relatively stiff foot supporting and receiving and ground engaging skid extension connected to the lower end of said frame and projecting therebelow at an angle thereto and extending forwardly of the line of the frame, said skid member being provided with means for directly receiving the upper part of the foot of the wearer thereupon and being sufficiently resilient to comfortably support the foot and lower leg of the wearer above a ground surface.

4. In a knee, leg and foot guard and supporting device for application upon the foot of a wearer the combination of a rigid elongated frame having means for attachment to the lower leg of the wearer for extension along the front of the shin bone of the wearer above the ankle, a foot receiving and supporting ground engaging member mounted at an angle to said frame and connected thereto for lengthwise adjustment upon the frame for extension therebelow and forwardly whereby to receive the foot of the wearer below the ankle joint and support the foot of the wearer in an elevated position above the ground when the wearer is in a kneeling position.
